FISHING LURE

George S. Perrin, Fort Smith, Ark., assignor to Plastics Research and Development Corp., Fort Smith, Ark., a corporation of Arkansas

Filed Oct. 21, 1968, Ser. No. 14,095

Term of patent 14 years

Int. Cl. D22—07

U.S. Cl. D22—27

Fig. 1.

Fig. 2.

Fig. 3.

Fig. 4.

Fig. 5.

Fig. 6.

FIG. 1 is a side elevational view of a fishing lure embodying my design, with sides of a body portion having a plurality of intersecting ridges forming a prismatic light reflecting finish and with hooks shown in broken lines being for illustrative purposes only.

FIG. 2 is a top plan view thereof.

FIG. 3 is a bottom plan view thereof.

FIG. 4 is a front elevational view thereof.

FIG. 5 is a rear elevational view thereof.

FIG. 6 is a transverse sectional view taken on line 6—6, FIG. 1 showing the opposed concave-convex surfaces thereof.

I claim:

The ornamental design for a fishing lure, as shown and described.
